HYDRAULIC MOTOR

Bernard C. Salchow, St. Paul, Minn., assignor to
Graco Inc., Minneapolis, Minn.

Filed Apr. 21, 1971, Ser. No. 136,303

Term of patent 14 years

Int. Cl. D15—99

U.S. Cl. D55—1

FIG. 1.

FIG. 2.

FIG. 3.

FIG. 4.

FIG. 5.

FIG. 6.

FIG. 1 is a right side view of a hydraulic motor showing my new design;

FIG. 2 is a back side thereof as viewed from the right side in the FIG. 1 view;

FIG. 3 is the opposite side view to the view of the motor shown in FIG. 1;

FIG. 4 is a front view of the motor of FIG. 1 as viewed from the left side thereof;

FIG. 5 is a bottom view of the motor of FIG. 1; and
FIG. 6 is a top view of the motor shown in FIG. 1.

I claim:

The ornamental design for a hydraulic motor, as shown and described.
